UNITED STATES PATENT OFFICE

JESSE D. LANGDON, OF LOS ANGELES, CALIFORNIA

RAZOR BLADE SHARPENER

Application filed July 14, 1928. Serial No. 292,787.

The present invention relates to razor blade sharpeners and aims to provide a novel and improved device of that kind by means of which the razor blade may be conveniently sharpened by inserting and withdrawing the blade.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Figure 1 is a plan view of a shaving kit, with the cover in open position, showing the blade sharpener.

Fig. 2 is a cross section on the line 2—2 of Fig. 1.

Fig. 3 is a section on the line 3—3 of Fig. 1 of the blade sharpener and blade holder.

Fig. 4 is a plan view of the blade holder.

Fig. 5 is a perspective view of the blade holder showing same partly opened.

The kit, which is more fully described in my copending application Serial No. 292,788, filed even date herewith, includes a case or box 10 having a hinged cover or top 11, and a U-shaped or horseshoe magnet 16 is disposed within the case.

The blade sharpener 17 comprises two plates 26 of suitable sheet metal disposed together and secured together in any suitable manner. As shown, opposite edges of the plates 26 are bent back around the companion edges, as at 27, for securing said plates together. The plates have the portions 28 offset away from one another and arranged vertically with the sharpener 17 disposed in the case 10 as shown. The offsets 28 provide pockets in which are disposed for rotation the pairs of rollers 29 composed of carborundum or any other suitable abrasive material. There are two pairs of abrasive rollers 29 for sharpening the opposite edges of a razor blade 25', inserted into the sharpener, and said pairs of rollers are so spaced apart that the edges of the blades pass directly between

the rollers. The plates 26 are spaced apart between the pairs of rollers 29 in order to receive the razor blade 25', thus providing a guide for the blade when introduced into the sharpener. In order to accommodate the blade holder 30, the plates 26 are provided between the offsets 28 with portions 31 offset away from one another and providing a guide to receive said blade holder for conveniently inserting and withdrawing the blade.

The blade holder 30 comprises the elongated members or plates 32 and 33 for holding the blade 25' between them, said members being narrower in width than the blade so that the edge portions of the blade project beyond the edges of said members. The members 32 and 33 are provided at one end with the angularly extending portions 34 and 35, respectively, which are hingedly connected, as at 36, thereby permitting the members 32 and 33 to be swung together and apart, and the portions 34 and 35 provide a finger piece for conveniently pushing the blade holder down into the sharpener and withdrawing the blade holder. The bend of the member 33 adjacent to the portion 35 is roughened, as at 37, in order to provide a grip for the thumb to conveniently swing the member 33 away from the member 32 and blade 25', as seen in Fig. 1.

Lugs 38 are struck from the member 32 to engage through the apertures 39 in the blade 25', for properly positioning said blade within the blade holder, and the member 33 has apertures 40 to receive the lugs 38 when the members 32 and 33 are swung together. The member 33 is slightly shorter than the member 32, in order that when the corresponding end of the member 32 and blade 25' are held between the thumb and first finger of one hand, as seen in Fig. 5, the opposite end of the holder may be held between the thumb and first finger of the other hand, for conveniently swinging the member 33 open, the first named thumb being beyond the end of the member 33, and the second named thumb being moved under pressure in engagement with the portion 37, to swing the member 33 away from the blade. The blade 25' may then be readily removed and replaced.

When a blade is disposed in the blade holder 30, the blade may be readily introduced into the sharpener 17, the holder 30 moving downwardly in the offsets 31 so as to guide the blade holder and blade in the sharpener. The edges of the blade are therefore moved longitudinally between the abrasive rollers 29 in order to sharpen the blade. The rollers 29 will also hollow-grind the edge portions of the blade because the rollers present convex surfaces to the blade. The blade may be reciprocated while in the sharpener, but it may usually be sufficient to slide the blade with the blade holder into the sharpener and then withdraw the blade.

The sharpener 17 being located at the terminals of the magnet 16 will also result in the magnetic flux acting on the edge portions of the blade 25' while it is in the sharpener.

The rollers 29 may also rotate in order to present the peripheral surface of the rollers to the blades throughout the peripheries of the rollers. The sharpening blade holder 30 may be deposited within the sharpener 17 when the device is not in use, and the abrasive rollers 29 may also be readily removed and replaced when worn out.

Having thus described the invention, what is claimed as new is:—

1. A razor blade sharpener embodying two plates disposed side by side and having pairs of spaced offsets, and abrasive members seated in said offsets for the longitudinal movement therebetween of the opposite edges of a razor blade, at least one of said plates having an offset between the first named offsets for the guiding movement of a blade holder.

2. A razor blade sharpener embodying two plates disposed side by side and having pairs of offsets, and abrasive rollers seated in said offsets and arranged for the longitudinal movement therebetween of the opposite edges of a razor blade, said plates being spaced apart between said offsets to receive the blade and at least one of the plates having an offset between the first named offsets for the guiding movement of a blade holder.

In testimony whereof I hereunto affix my signature.

JESSE D. LANGDON.
